[57] CLAIM

The ornamental design for a plant pot hanger, as shown and described.

DESCRIPTION

FIG. 1 is a perspective front view of a plant pot hanger showing my new design, shown broken away to disclose indeterminate length, it being understood that the perspective rear view is substantially a mirror image;

FIG. 2 is a plan thereof;

FIG. 3 is a side view thereof;

FIG. 4 is a perspective front view of a second embodiment of a plant pot hanger, shown broken away to disclose indeterminate length, it being understood that the perspective rear view is substantially a mirror image;

FIG. 5 is a plan view of FIG. 4; and,

FIG. 6 is a side view of FIG. 4.
